United States Patent Office

Des. 175,450
Patented Aug. 23, 1955

175,450

SCRAPER OR LIKE ARTICLE

Alexander C. H. Weiss, Takoma Park, Md., assignor to the United States of America as represented by the Secretary of the Army

Application November 6, 1953, Serial No. 27,486

Term of patent 14 years

(Cl. D9—6)

(Granted under Title 35, U. S. Code (1952), sec. 266)

The invention described herein may be manufactured and used by or for the Government for governmental purposes without the payment of any royalty thereon.

I claim:

The ornamental design for a scraper or like article, as shown.
